United States Patent Office

Des. 202,659

Patented Oct. 26, 1965

202,659

RETINOSCOPE OR SIMILAR ARTICLE

Willy Herold, Munich, Germany, assignor to Optische Werke G. Rodenstock, Munich, Germany

Filed Jan. 6, 1965, Ser. No. 83,294

Term of patent 14 years

(Cl. D57—1)

FIG. 1

FIG. 2

FIG. 3

FIG. 4

INVENTOR

FIG. 1 is a top plan view of a retinoscope or similar article, showing my new design, the bottom plan view being substantially identical therewith;

FIG. 2 is a front elevational view of the device of FIG. 1 embodying my new design;

FIG. 3 is a left side elevational view of the device embodying my new design; and

FIG. 4 is a right side elevational view of the device embodying my new design.

I claim:

The ornamental design for a retinoscope or similar article, as shown and described.
